UNITED STATES PATENT OFFICE.

LYMAN F. PONTIOUS, OF ADAIR, ILLINOIS.

DRAIN-TILE-DITCH LEVEL.

SPECIFICATION forming part of Letters Patent No. 281,183, dated July 10, 1883.

Application filed April 20, 1883. (No model.)

To all whom it may concern:

Be it known that I, LYMAN F. PONTIOUS, of 5
Adair, in the county of McDonough and State
of Illinois, have invented a new and Improved
5 Drain-Tile-Ditch Level, of which the follow-
ing is a full, clear, and exact description.

My invention consists of a device by which
to take the inclination of the ground to be
drained and set a spirit-level to show the said
10 inclination on the stock to which the level is
attached, the said stock being provided with
legs whereon to set it for ascertaining the in-
clination, which legs are also adapted for be-
ing so adjusted to the stock that they serve
15 for a handle by which the stock can be con-
veniently laid on the bottom of the ditch to
gage the inclination by a person standing on
the bank, all as hereinafter fully described.

Reference is to be had to the accompanying
20 drawings, forming part of this specification, in
which similar letters of reference indicate cor-
responding parts in all the figures.

Figure 1 is a side elevation of the device in
the position in which it is used to ascertain
25 the inclination of the ground to be drained,
for a guide by which to gage the inclination
of the bottom of the tile-ditch. It also repre-
sents a profile of the ground to be drained.
Fig. 2 is a side elevation of the device in the
30 position for gaging the bottom of the ditch,
with a part in section; and Fig. 3 is a plan
view of the device as represented in Fig. 2,
without the leg or handle attachment.

To a wood stock, *a*, of similar construction
35 as is commonly used for a carpenter's or
mason's spirit-level, but preferably of larger or
longer dimensions, I arrange a bubble-vial, *b*,
in a recess, *c*, under a top plate, *d*, on a pivot,
e, at one end, so that it may swing downward
40 from the plate *d* at the other end, where it is
provided with a binding-screw, *f*, projecting
out through a slot, *g*, in the side of the stock,
suitably for fastening the vial *b* at any desired
point, the said bubble-vial being level with
45 the stock when the free end is shifted up to
and fastened against the top plate, *d*. This
bubble-vial is preferably located about mid-
way between one end and the middle of the
stock, and at the middle of said stock I have
50 an eyebolt, *h*, extending through the stock, and
a metal washer, *i*, with a binding-nut, *j*, on the
other side, by which to secure the stock to a

supporting-rod, *k*, on which the stock may be
shifted up and down the whole length of the
rod, or nearly so, and the stock may also be 55
turned on the rod to level the stock or incline
it either way from the level. In order to bind
the rods against the washers, the eyebolts have
their eyes drawn partially through the washers,
as shown in Fig. 3 of the drawings. This 60
supporting rod or leg *k* has a brace, *l*, of simi-
lar character, jointed to it at *m*, near the upper
end, for steadyng the stock when set up on rod
k for use, both the rod and the brace being
pointed to set in the ground. The top of the 65
supporting-rod *k* is provided with a handle, *o*,
for a convenient means of handling the device
when used for gaging the bottom of the ditch.

Near the end opposite to where the bubble- 70
vial is mounted the stock is provided with an
other eyebolt, *p*, having a binding-nut, *q*, and
a washer, *s*, to connect the brace *l*, the same as
support *k* is connected when the device is used
for gaging the ditch. In the first place, to ob-
tain the inclination of the ground to be drained, 75
I set up the level on the rod *k* and brace *l*, as
in Fig. 1, where the lower end of the drain is
to be, then set up a stake, *t*, at the upper end,
or thereabout, the stake being of the same
height as the height of the level on the rod *k*, 80
and set the stock of the level to the inclina-
tion of the sight-line from the stock to the top
of the stake. Then I adjust the bubble-vial
by shifting its fore end down until the bubble
shows level, and fasten it in that position. Then 85
I attach the supporting-rod and brace, at their
lower ends, to the stock by the eyebolts *h* and
p, for a handle, as in Fig. 2, by which to lower
the level into the ditch from the bank when-
ever it may be required to gage the bottom by 90
the level, which will have the proper inclina-
tion when the bubble shows level, said bubble-
vial being inclined to the stock, as above stated.

The special merit of this invention is that
the device is an ordinary level when the bub- 95
ble-vial is set up against the top plate, while
by the manner of its adjustability on the sup-
porting-rod and of the bubble-vial it is a grad-
ing-level, and by the contrivance for using it
in the ditch it is a convenient and practical 100
gage for grading the ditch.

My improved level is also useful for tiling
or ditching level land, as follows: An outlet
for a drain on level land can frequently be

had, and in such cases a main tile can be laid down five or six feet deep along one side of the field, if an outlet is found into some slough or gully; then tile can be laid from this main tile out into the field at suitable distances apart, all connected with the main tile, which, being down deep, would give sufficient fall to the other tiles for long distances—say from forty to eighty rods or more. To use my level for this purpose all that is needed is to make the stake *t* longer—say, if the main tile is six feet deep, and the branch tile connected with it and to run out across the field, say, forty rods or more, is to end within, say, a foot of the top of the ground, all that is necessary is to add five feet to length of stake *t*—that is, make it five feet higher than the distance from the top of the level-stock to the ground; then take sight at the top of stake and set the level, as before.

When the rods are taken out of the eyes and laid down with the level-stock and tied to it, the level is then convenient to ship or carry about.

Having thus described my invention, I claim 25 as new and desire to secure by Letters Patent—

1. The stock *a*, having the adjustable bubble-vial *b*, and adjusting supporting-eyebolt *h*, and washer *i*, in combination with the supporting-rod *k* and brace *l*, substantially as described.

2. The stock *a*, having the adjustable bubble-vial *b*, and adjusting supporting-eyebolts *h p*, and washers *i s*, in combination with the supporting-rod *k* and brace *l*, substantially as 35 described.

3. The stock *a*, having the adjustable bubble-vial *b*, and adjusting supporting devices *h p* and *i s*, in combination with the supporting-rod *k*, brace *l*, and handle *o*, substantially as 40 described.

LYMAN F. PONTIOUS.
